AIR COOLED INTERNAL-COMBUSTION ENGINE

Elmer C. Kickhaefer, Cedarburg, Wis.

Application February 14, 1952, Serial No. 271,506

8 Claims. (Cl. 123—41.6)

This invention relates to internal-combustion engines and particularly to air-cooling systems therefor.

The invention provides an impeller of centrifugal operation having a number of axial discharges whereby the air may be more easily directed as required to the cylinders of the engine, and particularly the more remote of two or more cylinders arranged in-line and both sides thereof.

An object of the invention is to provide for delivery of equal amounts of air to each of the cylinders of an in-line engine at all speeds, particularly at idling as well as at high speed and to both sides of the engine in the required amounts.

A further object is to reduce substantially the vanes and ducts normally required to effect equal cooling of the several cylinders.

Another object is to provide control of the axial air discharge of the impeller to reach the remote cylinders of the engine.

Another object is to provide for the easier maintenance of the impeller and easier access to the impeller blades and the casing.

A further object is to provide an impeller casing which is self-cleaning and more readily suited for use in chain saw engines and the like.

Another object is to mount the impeller on the engine shaft and over the magneto and provide for delivery of air to the engine cylinders for cooling with substantial efficiency.

These and other objects and advantages will be more fully set forth in the following description of a preferred embodiment of the invention as illustrated in the accompanying drawing.

In the drawing:

Fig. 1 is a top plan view of the engine with parts thereof broken away and sectioned to show the magneto and details of construction of the impeller casing and scroll;

Fig. 2 is a side elevation of the engine with the impeller casing removed and with the scroll broken away and sectioned to show the scroll configuration in relation to the cut off sheet;

Fig. 3 is a transverse section through the engine looking toward the scroll member and with the latter partially broken away and sectioned; and

Fig. 4 is a front elevation of the engine and impeller casing with a part of the latter broken away to show the impeller and scroll member.

The engine 1 shown in the drawings includes the crankcase 2 which carries the horizontal crankshaft 3. The two cylinders 4 and 5 are arranged in-line and extend horizontally on one side of the engine.

Engine 1 is of two-cycle operation and is provided with separate crank chambers for each of cylinders 4 and 5, and which are adapted to receive a fuel and air mixture from the carburetor 6 for precompression with each power stroke of the piston operating in the corresponding cylinder.

The piston 7 operating in cylinder 4 and the crank chamber 8 which encloses the crank throw of crankshaft 3 to which piston 7 is connected, are shown in Fig. 3.

The ports 9 in the underside of cylinder 4 are uncovered by the respective pistons at the end of the power stroke for the exhaust discharge. The inlet ports 10 are located above ports 9 to be opened at the same time by the piston to allow transfer of the compressed fuel

2

and air from the corresponding crank-chamber 8 through the passage 11 into the cylinder for scavenging and recharging as the cylinder is exhausted.

The spark plug 12 of each cylinder 4 and 5 is energized by the magneto unit 13 which is supported by the circular flange 14 at the forward end of the engine. The two-cycle operation of the engine allows the magneto to be directly mounted on the crankshaft 3 for operation.

The rotor 15 and cam 16 of the magneto are fixed on the shaft 17 or overhanging end journal of crankshaft 3 which is supported in the bearing 18 adjacent to the rotor and cam. The stators 19 are mounted on the plate 20 which latter carries the timing means 21 operated by the cam 16. Plate 20 is mounted on flange 14 for rotational adjustment on the crankshaft axis whereby the timing of the ignition may be adjusted in relation to the reciprocation of the pistons.

The external flanges 22 of cylinders 4 and 5 provide the heat dissipation necessary for cooling of the cylinders by passing air over the cylinders and between the flanges. The flanges are formed integrally with the outer cast portion of cylinders 4 and 5 and extend radially thereof. The flanges are arranged in a series extending the length of the cylinders over passages 11 formed therein and surround ports 9 thereof.

The air is supplied by the impeller 23 which is mounted on shaft 17 of the crankshaft 3 to rotate therewith. Impeller 23 includes the bushing 24 which is mounted directly on the tapered portion 25 of shaft 17 and extends over the reduced and threaded end 26 of the shaft.

The hub portion 27 of the impeller mounted on bushing 24 and the skirt 28 are annularly formed and extend over the magneto 13. The radial vanes 29 of the impeller are formed integrally with hub 27 and skirt 28 and extend to the edge of the skirt. The forward inner ends of the vanes are radially spaced from the axis of rotation of the impeller. The nut 30 which is turned in one direction on the threaded end 26 of shaft 17 secures the impeller on bushing 24 and the bushing on the tapered portion 25 of shaft 17.

If desired, nut 30 may be fitted within bushing 24 to engage and withdraw the same for removal of the impeller from the shaft by turning nut 30 in the opposite direction.

According to the invention, the outer edge of each vane is generally arcuate to fit within the hemispherical casing 31 supported by the scroll plate 32. Plate 32 comprises preferably a single cast member forming a part of crankcase 2 and supporting the bearing 18 for shaft 17. The outer dimension of plate 32 is generally circular and includes a projecting wall 33 which extends alongside and to the end of the cylinder 4 adjacent thereto. The annular flange 34 of plate 32 projects forwardly of the engine and is provided with a marginal recess 35 in the front outer edge thereof to receive the circumferential offset margin 36 of casing 31 with a tight fit and to support the casing. The several spaced lugs 37 extending from the plate into the casing are drilled and tapped to receive the screws 38 for securing the casing thereto.

Casing 31 as provided is readily removable by removing screws 38 and has a spherical interior surface which is unobstructed for wiping clean at frequent intervals of the impeller with maximum efficiency and a minimum pressure loss due to friction.

The hemispherical casing 31 is readily adapted to be variously formed, e. g. stamped, spun, or die-cast. The casing 31 shown in the drawings is spun as a bowl with the offset margin 36 which fits the marginal recess 35 of plate 32 as described. The central air inlet of the casing comprises a plurality of holes 39 which are of a size and number to allow a relatively free air intake while excluding foreign matter such as wood chips, leaves and the like.

If desired a screen of any suitable mesh may also be mounted over the air inlet or substituted for the series of holes shown.

The interior spherical dimension of casing 31 is larger than the outlines of vanes 29 allowing throughout a minimum clearance therebetween sufficient for relative free movement. The casing is dismounted from plate 32 by

removing screws 38 which with removal of the casing allows access to impeller 23 and the interior and outlets 40 and 41 of plate 32. The removal of impeller 23 thereafter provides unrestricted access to and from all sides of magneto unit 13.

The upper outlet opening 40 in plate 32 is located for discharge of air over cylinders 4 and 5. The hood 42 extends from the rear side of plate 32 to enclose opening 40 and extends over cylinders 4 and 5. Cover 43 extends from plate 32 under cylinders 4 and 5 and is provided with openings to accommodate the exhaust pipes 44 from each cylinder.

The lower outlet opening 41 in plate 32 is located to allow the air to pass therethrough in a direction beneath cylinders 4 and 5 and between cover 43 and the cylinders.

According to the invention the air is driven by centrifugal force axially into the scroll 45 formed in plate 32 and continues to move rotationally therein until reaching openings 40 or 41. Scroll 45 is of axial development and extends in a circle about the axis of rotation of the impeller and terminates at opening 40. A part of the air delivered by impeller 23 passes through opening 40 from scroll 45 or is deflected through opening 40 by the cut-off member 46 formed integrally with plate 32. Member 46 is angularly disposed and extends from opening 40 along the back side of wall 33 and adjacent to cylinder 4. The air passing through opening 40 into hood 42 blankets cylinders 4 and 5 with cooling air which passes over flanges 14 thereof towards the rear of the engine.

The cut-off member 47 is integrally formed with plate 32 and is angularly disposed to deflect air through opening 41. Member 47 projects within plate 32 towards the impeller into the rotationally moving air stream and delivery of the air necessary to cool the underside of the cylinder. The air from opening 41 passes between cylinders 4 and 5 and cover 43 towards the rear of the engine or through the openings in the cover provided for pipes 44. The separate streams of air passing over the cylinders from openings 40 and 41 cool the corresponding parts of the cylinders which include the transfer passages 11 and exhaust openings 9. The relative sizes and locations of openings 40 and 41 and members 46 and 47 provide a division of the cooling air delivered and provide the desired relative cooling of the exhaust-and-transfer-port sides of the cylinders. The air from both sides of the cylinders passes from between hood 42 and cover 43 at the rear of the engine.

In the embodiment shown, the proportion of air cooling the transfer port side of cylinders 4 and 5 increases with the speed of the engine and total air-delivery of impeller 23 to coincide with the general cooling requirements of the type of two-cycle engine shown and described.

Conditions of service such as in chain saw units, or where excessive dust and dirt are prevalent, create problems of frequent cleaning of the impeller and casing. The ease of removal of casing 31 which provides access to impeller 23 and the ease of cleaning the bowl-shaped casing particularly affords some assurance of the proper maintenance and cleaning necessary.

The impeller operates within casing 31 with a minimum of frictional losses which allows the magneto to be advantageously mounted on the crankshaft between the impeller and the engine without disadvantage. The air from the impeller and casing is discharged axially into scroll 44. The scroll is developed axially to outlet 40 from which the air is released. Without guide vanes, the air passes over cylinders 4 and 5 in substantially equal amounts.

The hemispherical casing is virtually self-cleaning by reason of the smooth inner contour and the axial discharge of the casing into the scroll plate. The discharge of air from the entire perimeter of the casing is allowed without obstruction with the exception only of the small lugs 37 which support the casing.

Various embodiments of the invention may be employed within the scope of the accompanying claims.

I claim:

1. In an internal combustion engine of the class described, a fan assembly for air cooling one or more cylinders of the engine, comprising an impeller mounted on one end of the engine crankshaft to rotate therewith and having a hub and extending skirt, a series of blades extending radially from said hub and axially along said skirt, a hemispherical casing for said impeller, said blades

having an outer dimension providing a minimum operating clearance with the interior of said casing and providing for the axial discharge of air from between said skirt and said casing, a scroll plate secured to and closing said casing at the periphery thereof and having a discharge opening adjacent to one of said cylinders, and a cut-off member extending along one side of said opening to direct the air to the side of said last named cylinder immediate thereto, the scroll of said member extending circularly to the adjacent side of said discharge opening and of axial development to receive the air from said casing and discharge the air through said opening in a direction toward the other side of said cylinder.

2. In an engine of the class described, a series of cylinders arranged in-line and having external fins for air-cooling, said cylinders having parts with dissimilar cooling requirements on corresponding sides, an impeller mounted on the projecting forward end of the engine crankshaft to rotate therewith and having a hub and extending skirt, a series of blades extending radially from said hub and axially along said skirt rearwardly toward said cylinders, a hemispherical casing for said impeller, said blades having an outer dimension providing a minimum operating clearance with the interior of said casing and for the axial discharge of air from between said skirt and said casing, a scroll plate secured to said engine to support said casing at the periphery thereof and having separate discharge openings adjacent to the forwardmost cylinder, and cut-off members carried by said plate at each opening thereof to direct given proportions of air to said parts of said forwardmost cylinder, said member including a scroll of axial development to receive the air from said casing and extending to one of said discharge openings to discharge the air through said opening in a direction rearwardly toward the rearwardly disposed of said cylinders.

3. In an engine of the class described, having a crankshaft and a magneto operatively mounted on said crankshaft forwardly of the engine, a series of cylinders arranged in-line and having external fins for air-cooling, an impeller mounted on said engine crankshaft to rotate therewith and having a hub and a skirt extending over said magneto, a series of blades extending radially from said hub and axially along said skirt rearwardly toward said cylinders, a hemispherical casing for said impeller, said blades having an outer dimension providing a minimum operating clearance with the interior of said casing and providing for the axial discharge of air from between said skirt and said casing, a scroll plate secured to said engine and between the latter and said magneto to support said casing at the periphery thereof, said plate having a discharge opening adjacent to the forwardmost cylinder and a cut-off member extending along one side of said casing at said opening to direct the air to the adjacent parts of said forwardmost cylinder, said plate having a scroll of axial development to receive the air from said casing and extending to said discharge opening to discharge the air through said opening in a direction rearwardly toward the rearwardly disposed of said cylinders.

4. In an engine of the class described, a series of cylinders arranged in-line and having external fins for air-cooling, an impeller mounted at the forward end of the engine crankshaft to rotate therewith and having a hub and a rearwardly extending skirt, a series of blades extending radially from said hub and axially along said skirt toward said cylinders, a hemispherical casing for said impeller and having a central screened inlet opening, said blades having an outer dimension providing a minimum operating clearance with the interior of said casing and disposed for the axial discharge of air from said casing, and a scroll member having a discharge opening adjacent to the cylinder immediate thereto and secured to said engine, said member having an annular flange fitting within the periphery of said casing to support the latter and allowing removal thereof for cleaning and access to said impeller.

5. In an engine of the class described, a series of cylinders arranged in-line and having external fins for air-cooling, an impeller mounted on the projecting forward end of the engine crankshaft to rotate therewith and having a hub and extending skirt, a series of blades extending radially from said hub and axially along said skirt rearwardly toward said cylinders, a hemispherical casing for said impeller and having a central screened inlet opening, said blades having an outer dimension providing

a minimum operating clearance with the interior of said casing and for the axial discharge of air from between said skirt and said casing, a scroll plate secured to said engine supporting said casing at the periphery thereof and having a discharge opening adjacent to the forwardmost cylinder, and a cut-off member extending along one side of said plate at the opening thereof to direct the air to the adjacent parts of said forwardmost cylinder, said plate including a scroll of axial development to receive the air from said casing and extending to said discharge opening to discharge the air through said opening in a direction rearwardly toward the rearwardly disposed said cylinders, said casing being adapted to be removed from said member for cleaning and access to said impeller.

6. In an engine of the class described, a series of cylinders arranged in-line and having external fins for air-cooling, said cylinders having parts with dissimilar cooling requirements on corresponding sides, an impeller mounted on the projecting forward end of the engine crankshaft to rotate therewith, a casing for said impeller, a scroll plate secured to said engine to support said casing at the periphery thereof and having separate discharge openings adjacent to the forwardmost cylinder, cut-off members carried by said plate at each opening thereof to direct given proportions of air to said parts of said forwardmost cylinder, and cover members extending over said cylinders and enclosing said openings to receive the air from said casing and direct the air over said corresponding parts of said cylinders in a direction rearwardly of said engine.

7. In an engine of the class described, a series of cylinders arranged in-line and having external fins for air-cooling, said cylinders having parts with dissimilar cooling requirements on corresponding sides, an impeller mounted on the projecting forward end of the engine crankshaft to rotate therewith, a casing for said impeller, a scroll plate secured to said engine to support said casing at the periphery thereof and having separate discharge openings adjacent to the forwardmost cylinder, 40 cutoff members carried by said plate at each opening

thereof to direct given proportions of air to said parts of said forwardmost cylinder, and cover members extending over said cylinders and enclosing said openings to receive the air from said casing and conduct the air over said 5 corresponding parts of said cylinders rearwardly of said engine, said plate including a scroll of axial development to receive the air axially from said casing and extending to the side of one of said discharge openings to discharge the air through said opening in a direction toward the 10 rearwardmost cylinder.

8. In an engine of the class described, a series of cylinders arranged in-line and having external fins for air-cooling, said cylinders having parts with dissimilar cooling requirements on corresponding sides, an impeller 15 mounted on the projecting forward end of the engine crankshaft to rotate therewith, a casing for said impeller, a scroll plate secured to said engine to support said casing at the periphery thereof and having separate discharge openings adjacent to the forwardmost cylinder, and cut-off members carried by said plate at each opening thereof 20 to direct given proportions of air to said parts of said forwardmost cylinder, said member including a scroll of axial development to receive the air from said casing and extending to one of said discharge openings to discharge 25 the air through said opening in a direction rearwardly toward the rearwardly disposed of said cylinders.
